UNITED STATES PATENT OFFICE

132,239

DESIGN FOR A DRESS ENSEMBLE

Philip Zahn, New York, N. Y.

Application March 30, 1942, Serial No. 106,370

Term of patent 3½ years

To all whom it may concern:

Be it known that I, Philip Zahn, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my new design,

Fig. 2 is a rear view of the dress ensemble shown in Fig. 1, and

Fig. 3 is an enlarged fragmentary side view of Fig. 1.

Fig. 4 is a front view of the dress member of the ensemble shown in Fig. 1, and

Fig. 5 is a rear view of the dress member of the ensemble shown in Fig. 1.

I claim:

The ornamental design for a dress ensemble, substantially as shown.
